PNEUMATIC MOTOR

Walter Jakowchuk, Melrose Park, Ill., assignor to Mead Specialties Company, Inc., Chicago, Ill.
Filed Feb. 4, 1963, Ser. No. 255,970
8 Claims. (Cl. 91—2)

This invention relates to a pneumatic motor, and, more particularly, to a pneumatic motor employed as part of a pneumatic timing device.

This invention has utility in connection with the type of timer seen in Mead Patent No. 2,946,346. There, a cam-equipped control device is seen to be operated by an electric motor. The instant invention provides a means for pneumatically driving the control device, and the provision of such constitutes and objective of this invention.

Another object of the invention is to provide a novel pneumatic motor employing a one-way rotary clutch operated by pneumatic cylinder and piston rod means so as to develop a clutch output of relatively slow speed whereby a sequence of events is adapted to be carefully regulated in a given time.

Still another object of the invention is to provide a novel pneumatic timer adapted for "one revolution" operation whereby a series of events can be timed according to one revolution of a control shaft, the shaft rotating slowly and only through one revolution until intentionally reactivated.

A further object of the invention is to provide a novel interlock bleed valve which finds utility, for example, in conjunction with the one-revolution operation just referred to.

Other objects and advantages of the invention may be seen in the details of construction and operation set down in this specification.

The invention is explained in conjunction with an illustrative embodiment in the accompanying drawings, in which—

FIG. 1 is a fragmentary top plan view of a pneumatic timer constructed according to the inventive teachings;

FIG. 2 is a fragmentary front elevational view of the apparatus of FIG. 1 such as would be seen along the sight line 2—2 as applied to FIG. 1;

FIG. 3 is a side elevational view, partially broken away, of a clutch employed in the apparatus of FIGS. 1 and 2;

FIGS. 4 and 5 are the left and right end elevational views of the clutch seen in FIG. 3;

FIG. 6 is an enlarged sectional view as seen along the line 6—6 of FIG. 1;

FIG. 7 is a sectional view taken along the line 7—7 of FIG. 6;

FIG. 8 is an elevational view, partially broken away, of a block employed in conjunction with the clutch of FIGS. 3—5 and which is also seen in FIG. 7;

FIG. 9 is an elevational view of a plate employed in conjunction with the clutch of the preceding views, with certain of the clutch elements being shown in dotted line;

FIG. 10 is a side elevational view, partially in section, of a directing valve employed in the apparatus of FIG. 1;

FIG. 11 is a sectional view, taken along the sight line 11—11 of FIG. 10;

FIG. 12 is an elevational view partially in section, of a manually-operated bleed valve employed in the apparatus of FIG. 1;

FIG. 13 is an elevational view, partially in section, of an interlocked bleed valve employed in the pneumatic circuitry of the invention;

FIG. 14 is a sectional view of a pressure fluid supply valve employed in the inventive arrangement;

2

FIG. 15 is a schematic view or diagram of the interconnection of the valves of FIGS. 10—14; and FIG. 16 is a schematic view of the actuating system of FIG. 1 with certain valves shown in section.

- 5 In the illustration given, and with particular reference to FIGS. 1 and 2, the numeral 20 designates generally a base or frame adapted to carry the inventive timer. The timer itself is seen at the upper right-hand portion of FIG. 1 and is generally designated by the numeral 21.
10 The timer 21 includes a line shaft 22 which is adapted to be driven through a gear train 23 by means of the inventive timer generally designated 24 and which is seen on the left-hand side of FIG. 1.

The piping and valving generally designated by the numeral 25 at the lower right-hand portion of FIG. 1 has to do with the previously referred-to "one revolution" operation, and description of this portion of the invention will occur later in this specification.

The entire timer is intended to be a self-contained unit, as can be appreciated from a consideration of FIG. 2, wherein the base is equipped with a cover, shown in dotted line and designated 26. The cover is apertured in the top to permit the extension of a control knob 27 employable to commence operation of the timer. The cover or casing 26 is also apertured as at 28 (still referring to FIG. 2) to permit extension of a conduit 29 for coupling to a source of pressure fluid (not shown). Normally, compressed air at shop line pressure of 80 p.s.i. is coupled to the conduit 29.

30 The output of the timer 24 is in the form of rotation of a spur gear 30 (see FIG. 2) which operates against a main gear 31 which is coupled to the line shaft 22. The gears 30 and 31 make up the gear train 23 previously referred to.

35 The timer 21 includes a plurality of poppet valves 32 which are actuated by cams 33 at various times according to the dictates of a processing operation. It will be seen that the timer 21 is generally of the type shown in the above-mentioned Mead Patent No. 2,946,346, and reference is hereby made to that patent for additional details of construction and operation not herein given.

The pneumatic motor will now be described, and this can be best appreciated from a consideration of FIGS. 6 and 7.

Pneumatic motor description

In FIG. 6, the base 20 is again designated and is seen to support a pair of cylinder and piston rod units 34 and 35. The unit 34 includes a cylindrical casing 36 interiorly equipped with a piston 37 from which extends a piston rod 38. Pressure fluid is supplied through a fitting 39.

In similar fashion, the unit 35 includes a casing 40 having a cylindrical interior 41 in which a piston 42 is slidable, the piston being equipped with a projecting piston rod 43. Fluid for the movement of the piston is provided through a port 44.

The piston rods 38 and 43 operate against a one-way rotary clutch generally designated 45, which is also seen in FIGS. 3—5 and 7.

60 Still referring to FIG. 6, it will be seen that the clutch 45 includes a block 46, the block 46 being shown alone in FIG. 8. The block 46 is seen to be bored as at 47 and 48 for the receipt of the piston rods 38 and 43, respectively. In operation, pressurizing the chamber 49 of the cylinder unit 34 results in movement of the piston 37 to the left, causing the block 46 to move accordingly, which necessarily causes the piston rod 43 and its associated piston 42 also to move to the left—at this stage the cylinder chamber 41 of the cylinder unit 45 being vented to atmosphere through a piping system to be described hereinafter. The operation of the invention

further contemplates that after the piston 47 has been moved to its full left position, compressed air will be supplied to the unit 35, while the unit 34 is vented so as to cause a movement of the system just described to the right. Thus, the block 46 is reciprocated over the throw of the piston rods 38 and 43 which are mounted in coaxial relation.

The reciprocating movement of the block 46 is converted into rotary motion by the remainder of the clutch 45, resulting in slow or stepwise rotation of the motor shaft 50.

The motor shaft 50 is mounted in a pair of bearings 51 and 52 (see FIG. 7), with the bearings 51 and 52 being supported on the frame 20. The clutch 45, as seen in FIG. 7, is interposed between the spaced-apart bearings 51 and 52 and the block 46 is slotted as at 53 to accommodate the extension of the shaft 50 therethrough.

The shaft 50, in the intermediate longitudinal portion extending through the clutch 45, is equipped with a hexagonal sleeve 54 secured thereto by means of a set-screw 55 (see FIG. 6). Mounted on the sleeve 54 and constituting part of the clutch 45 are a pair of clutch plates 56 and 57 (see FIGS. 7 and 9). Each plate 56 and 57 is equipped with perimetrically spaced slots as at 58, in which discs 59 are positioned.

Providing the means for turning the clutch plates 56 and 57 through the discs 59, are a pair of drive plates 60 and 61. The plate 61 is partially broken away in FIG. 6 to show the arrangement of the elements 57 and 59, the discs 59 being urged to a nonclutching position by means of springs 62. Still referring to FIG. 6, it will be seen that the drive plate 61 is pivotally mounted on the block 46 by means of a stud 63. The stud 63, as well as an identical stud 64 employed in conjunction with the drive plate 60, can be seen in FIG. 3. The studs 63 and 64 are received within bores 65 and 66, respectively (see also FIG. 8), and are releasably held by means of resilient ring washers 67. The various plates, discs, and blocks are maintained as a compact unit by means of retaining rings 68 (see FIGS. 3-5). In FIG. 7, it is seen that retaining plates 60a and 60b confine the discs 59 and springs 62 associated with drive plate 60, while the retaining plates 61a and 61b perform the same function for drive plate 61.

In the operation of the clutch 45, shifting of the block 46 one way or the other in FIG. 6 results in an engagement between either the plates 61 and 57, or 60 and 56, as the case may be. For example, movement of the block 46 to the right—as where the chamber 41 is pressurized—causes the plate 61 to pivot on the stud 63 and urges the discs 59 against the plate 57 so as to turn the shaft 50. On the other hand, this same movement to the right has no effect on the plate 56, since the drive plate 60 is not effective to urge the discs 59 against the clutch plate 56. However, on the return stroke—as where the chamber 49 is pressurized—the reverse is true, i.e., the clutch 56 being driven by the drive plate 60, which imparts further rotational movement to the shaft 50. As can be appreciated from the arrows applied to FIGS. 4 and 5, the pivoting movement of the drive plates 60 and 61 are accumulative, and, in the illustration given, the strokes are short, so that approximately 125 actuations of the two cylinders 34 and 35 are required to cause one revolution of the shaft 50. The pivotal movement of the drive plates 60 and 61 is a departure from straight-line motion, but because of the shortness of the stroke and the fact that the action takes place at the top and bottom of the arcs, this departure from straight-line motion is unobjectionable.

To provide the alternate actuation of the cylinder and piston rod units 34 and 35, the block 46 is equipped with projecting pins 69 and 70 mounted in bores 71 and 72, respectively. The pins 69 and 70 operate against the balls 74 and 75 of poppet valves 76 and 77, respec-

tively, so as to vent a first air-directing valve generally designated 78.

The valve 78 is seen in FIG. 1 and is connected by means of flexible conduits 79 and 80 to the poppet valves 76 and 77. The poppet valves 76 and 77 are supported on brackets 81 and 82 (see FIG. 6) which are mounted on the cylinder units 34 and 35.

The air-directing valve 78 is also coupled by means of flexible conduits 83 and 84 to the fittings 39 and 44 provided as part of the air cylinders 34 and 35.

The air-directing valve 78 is seen in FIGS. 10 and 11, where the valve includes a pilot body 85 and a main body 86 suitably secured together by means of bolts 86a. For additional details on this valve, Lieser Patent No. 2,946,321 may be consulted.

The pilot body portion of the valve is equipped with a bore or chamber 87 in which a pilot spool 88 is slidably mounted. The function of the pilot spool 88 is to position a slide valve 89 in either one of two positions so as to cause compressed air to flow out of one or the other of outlet ports 90 or 91. The air enters through an inlet as at 92 (see also FIG. 1) and flows through an annular recess 93 into the chamber 94. As such, it communicates with an L-shaped passage 95 (see FIG. 11) so as to issue out of the port 90 when the pilot spool 88 is in the position seen in FIG. 10. In other words, when the pilot is at the left, compressed air issues out of the left port.

To move the pilot spool to the right in FIG. 10, it is only necessary to vent the port 96, which is seen to be coupled to the poppet valve 76. The characteristic of the valve seen in FIGS. 10 and 11 is that the pilot stays in a given end position until the other end is vented, both ends being under the same pressure by virtue of the longitudinal bore 97.

Operation of pneumatic motor

Referring now to FIG. 1, the operation of the pneumatic motor 24 is seen to involve the following: A pressure fluid (usually compressed air) is supplied to the directing valve 78 by means of the conduit 93. As soon as this happens, air is vented through the poppet 76 to cause the pilot spool 88 to move upwardly (in FIG. 1) and thus supply compressed air through the conduit 83 to the air cylinder 35. This results in movement of the block 46 downwardly until the pin 70 engages the poppet 77, initiate another shift of the pilot spool 88, which then vents the air cylinder 35 through the port 99 (see FIG. 11) and pressurizes the air cylinder 34 through the conduit 84.

In the commercial form of the invention, the clutch 45 is a Pos-O-Grip Clutch manufactured by Machine Accessories, Inc., of Minneapolis, Minnesota, and by adjusting the air pressure and exhaust from valve 78, speeds from zero to 300 r.p.m. at 25 p.s.i. inlet pressure are obtained. The shaft 50 is coupled through a 10:1 gear reduction train as at 23, so that the line shaft speed may be varied from zero to 30 r.p.m.

The foregoing apparatus is particularly useful where there is a repeated sequence of operations, the various operations differing in time. However, upon occasion it is desirable to provide just a single sequence of timed operations, in which case the previously-referred-to "one revolution" feature is employed. For this purpose, I provide a novel piping and valving arrangement to restrict the arcuate movement of the line shaft 22 to one precise revolution.

For this purpose, the line shaft 22 is equipped with an extra cam as at 100 (see FIG. 1), which is arranged to depress a plunger 101 provided as part of an on-off valve generally designated 102 and which is seen in FIG. 14. The valve 102 (as seen in FIG. 1) is equipped with a muffler 103 to reduce the noise level of the exhaust, the muffler being threadedly received within a transverse threaded bore 104 (see FIG. 14). Compressed air from the fitting 29 enters a T 105 (see FIGS. 1 and 2), and by means of flexible conduit 106, enters the top or end bore

107 (see FIG. 14) of the valve 102. In the condition seen in FIG. 14, air entering the bore 107 is precluded by virtue of the position of plunger 101 from flowing through the valve and exiting from the outlet port 108. The outlet port 108 provided on the other end or bottom as seen in FIG. 1, communicates by means of flexible pipe 109 to an interlock bleed valve generally designated 110 and which is also seen in FIG. 13. When the plunger 101 is depressed, compressed air flows through the valve 102 to the valve 110 to actuate the latter. This will occur whenever the cam 100 engages the plunger 101, and the valve 110 is arranged to be responsive to the steady air pressure from valve 102 but to only momentarily bleed a second air directing valve generally designated 111. The valves 111 and 78 are substantially the same except for the location of the exhausts. In the valve 111, the exhaust 112 is opposite to the inlet 113, while in the valve 78 the exhaust 92' is on the same side as the air inlet port 92. However, the interior of the valves, including the pilot spools and slide valve elements, are the same.

The valve 111 has within it a spool 88 which is normally positioned in the upward or dotted line position designated 88' in FIG. 1. When the line shaft 22 is rotating (as pictured in FIG. 1, since the cam 100 is not against the plunger 101), the pilot spool in the valve 111 is in its lower position so as to direct air from the inlet 113 through the line 98 to the directing valve 78.

At the completion of one revolution, the depression of the plunger 101 by the cam 100 results in a momentary bleed of the port 114 of the directing valve 111 so as to position the spool in the position designated 88'. This cuts off flow of compressed air through the directing valve 78 and shuts down the timer. The timer is restarted by depressing the plunger 27 which is provided as part of another on-off valve seen in FIG. 12. Normally, the valve is in the off position shown, wherein the valve stem 115 engages a seat 116, thereby isolating the inlet port 117 from the outlet port 118. Momentary depression of the handle 27 brings these two ports into communication and vents the port 119 of the valve 11, permitting the pilot spool to move from the 88' position and direct compressed air from the T 105 to the directing valve 78. This then initiates another cycle of operation, i.e., one revolution to shaft 22.

The interlock bleed valve 110 provides an important function of performing a momentary bleed while being under continuous pressure, it being apparent that the valve 102 is maintained in an open condition by virtue of the continuous depression of the plunger 101. This stems from the fact that the cam 100 comes to a stop in contact with the plunger 101 so that compressed air from the line 106 exerts a continuous pressure on the interior of the valve 110 by means of the inlet port 120.

Referring now to FIG. 13, the numeral 121 designates a tubular body which is equipped with a longitudinally-extending bore 122. The bore is closed at one end as at 123 by means of a plug equipped with a suitable O-ring seal 124, the plug being threaded received on the threads 125 provided on the interior of the bore 122.

The opposite end of the bore provides the port 120, and mounted within the bore is a larger spool 126 adjacent the closed end. The spool 126 itself has an axially-extending bore 127 and an upstanding hollow post 128 extending axially toward the open end equipped with the port 120.

The bore 122 is equipped with a second spool 129 also equipped with a through bore 130. The spool 129, midway of its length, is equipped with an annular, inwardly-extending shoulder 131 which provides a seat for a ball check valve 132. The ball 132 is urged against the seat by means of a coil spring 133. The spools 129 and 126 are urged apart by a second and heavier coil spring 134 which is partially received within both spools and which surrounds the hollow post 128.

In operation, two transverse bores are provided, one at 135 which receives a fitting 136 communicating with

the flow port 114 of the directing valve 111 of FIG. 1. The other transverse bore includes opposite openings 137 spaced toward the closed end 123 from the first bore 135.

5 Between the two transverse bores 135 and 137, the body 121 provides an annular seal as at 138 operating against the smaller diameter spool 129.

In operation, compressed air flows into the port 120 from the valve 102. This air cannot flow longitudinally 10 through the smaller diameter spool 129 because of the closed position of the ball check valve 132. This results in the smaller diameter or inner spool 129 being urged to the right in FIG. 13 into further telescoping relation with the larger spool 126. Ultimately, this brings the 15 hollow post 128 into engagement with the ball check valve 132 so as to upset the same, i.e., remove it from its seated position on the seat 131. Thereupon, compressed air is able to flow through the bore 139 of the hollow post 128 and through the constricted bore 140 into 20 the space 141 adjacent the closed end 123 of the valve 110. This serves to move the larger spool 126 to the left, which necessarily returns the inner spool 129 to its original position. During the reciprocatory movement of the inner spool 129, the seal developed by the O-ring 142 and the outer surface of the inner spool 129 is broken so that communication is established between the 25 ports 135 and 137, thereby providing a momentary or short term venting of the pilot chamber in valve 111.

So long as air pressure is applied to the interior of 30 the valve 110 by virtue of the valve 102 being maintained in open condition, the outer spool 126 is maintained in its left position, i.e., from that shown, and, because of the influence of the compressed air in the chamber portion 141.

35 When the handle or plunger 27 is operated to commence the one-revolution operation, the valve 102 is changed to the condition seen in FIG. 14, wherein the port 108 is connected to the port 104, valve 110 thereby being exhausted to atmosphere. This removes all pressure from the line 109 (see FIG. 1) and from the chamber portion 141, permitting the coiled spring 134 to return the outer spool 126 to the position shown. Any air trapped within the inner spool and to the right of the ball check valve 132 is vented through the ports 142. 40 The interlocked bleed valve 110 thus is returned to the FIG. 13 condition so as to be ready for stopping the rotation of the shaft 22 when the cam 110 completes its travel and once again engages the plunger 101.

While, in the foregoing specification, a detailed description of an embodiment of the invention has been set down for the purpose of explanation, many variations in the details herein given may be made by those skilled in the art without departing from the spirit and scope of the invention.

55 I claim:

1. A pneumatic motor adapted to power a pneumatic timer, comprising:
a frame equipped with spaced bearings, a shaft journaled in said bearings and adapted to be coupled to said timer,
60 a one-way rotary clutch coupled to said shaft between said bearings, said clutch including a block adapted to reciprocate transversely to the axis of said shaft to provide a few degrees of shaft rotation for each reciprocation,
a pair of pneumatic cylinder and piston rod units mounted on said frame in alignment with said block on opposite sides thereof and coupled thereto for reciprocating the same, and
65 means including a source of pressure fluid and a directing valve for alternately delivering pressure fluid to said pneumatic cylinder and piston rod units for exhausting pressure fluid therefrom, said alternately delivering means including a pair of poppet valves mounted on said frame, one on each side of said block

and engageable sequentially thereby during reciprocation thereof for controlling said directing valve.

2. The structure of claim 1 in which a plurality of cams are operatively connected to said shaft, and valve means operatively associated with one of said cams for stopping the flow of pressure fluid to said directing valve after a predetermined arcuate movement of said shaft.

3. The structure of claim 2 in which said valve means includes a second directing valve for delivering pressure fluid to the first-mentioned directing valve, said second directing valve including a pilot-equipped chamber for directing the flow of pressure fluid through said second directing valve, a momentary bleed valve connected to one side of said chamber and actuated by said one cam to move said pilot in one direction, and means for bleeding pressure fluid from the other side of said chamber to move said pilot in the opposite direction.

4. A pneumatic motor adapted to power a pneumatic timer, comprising:

a frame equipped with spaced bearings, a shaft journaled in said bearings and adapted to be coupled to said timer, a one-way rotary clutch coupled to said shaft between said bearings, said clutch including a block adapted to reciprocate transversely to the axis of said shaft to provide a few degrees of shaft rotation for each block reciprocation;

a pair of pneumatic cylinder and piston rod units mounted on said frame in alignment with and on opposite sides of said block and coupled thereto for reciprocating the same;

a source of pressure fluid and a directing valve coupled to said source, said directing valve being equipped with a pilot arranged to direct pressure fluid alternately to said unit while exhausting pressure fluid from the unit not receiving pressure fluid, and

a pair of poppet valves mounted on said frame on opposite sides of said block so as to be adjacent to one of said pneumatic cylinder and piston rod units, said poppet valves being coupled to said directing valve for positioning said pilot as a function of the reciprocation of said block.

5. The structure of claim 2 in which said valve means includes first and second valves, said first valve being engageable by said one cam and being coupled to said source of pressure fluid, said second valve being coupled to said first valve for receiving pressure fluid therefrom for stopping the flow of pressure fluid to said directing valve.

6. In a pneumatic motor, a frame, a shaft mounted for rotation on said frame, a one-way rotary clutch coupled to said shaft, a pair of oppositely-acting pneumatic cylinder and piston rod units operatively connected to said clutch for rotating said clutch a few degrees for each piston rod stroke, said clutch including a block ar-

ranged for reciprocal movement transverse to said shaft, said units being arranged for piston rod movement transverse to said shaft, with said block being equipped with oppositely disposed bores receiving said piston rods, and means including a source of pressure fluid for alternately stroking said piston rods, said stroking means comprising a directing valve equipped with a two-position pilot for alternating the valve condition to alternately deliver pressure fluid to one unit while exhausting pressure fluid from the other unit, and a pair of poppet valves on said frame in juxtaposition with said clutch and actuated by said clutch to move said pilot from one position to the other and thereby cause said directing valve to alternately deliver pressure fluid to said units, said poppet valves being positioned above said units and alternately engageable by said block at the limits of its reciprocatory travel.

7. The structure of claim 6 in which said frame is equipped with means for limiting the operation of said stroking means upon the completion of one revolution of said shaft, said limiting means includes valve means coupled to said shaft for stopping the flow of pressure fluid to said stroking means.

8. In a pneumatic motor, a frame, a shaft mounted for rotation on said frame, a plurality of cams on said shaft, a plurality of valves on said frame, one for each cam and actuated thereby, a one-way rotary clutch coupled to said shaft, a pair of oppositely-acting pneumatic cylinder and piston rod units operatively connected to said clutch for rotating said clutch a few degrees for each piston rod stroke, and means including a source of regulated pressure fluid for alternately stroking said piston rods whereby the rotational speed of said shaft can be varied gradually without change of mechanical parts.
